ARTHUR C. EASTWOOD, OF CLEVELAND, OHIO.

CURRENT-CONTROLLING SYSTEM.

SPECIFICATION forming part of Letters Patent No. 779,267, dated January 3, 1905.

Application filed August 9, 1904. Serial No. 220,138.

To all whom it may concern:

Be it known that I, ARTHUR C. EASTWOOD, a citizen of the United States, residing in Cleveland, Ohio, have invented certain Improvements in Current-Controlling Systems; of which the following is a specification:

One object of my invention is to provide such a combination of electrical apparatus, which in the present instance is employed in connection with an electric motor, as will under operating conditions prevent injury to the motor and to the machine operated thereby even though an excessive load be applied to said machine.

15. A further object of the invention is to provide a motor-controlling system with an automatically-operating current-limiting device, so arranged and connected that the motor will be placed in circuit with a protective device 20 when its load is increased to a predetermined extent and will be automatically accelerated to full speed when said load is decreased by a predetermined amount.

Another object of the invention is to provide an electrical device, such as a motor, with a bank of resistance and automatically-operating switches for short-circuiting the same, together with an automatically-operating switch for controlling the operation of the 25 short-circuiting switches, so arranged that when current flowing to the motor exceeds a predetermined amount the automatic switch operates to cause the short-circuiting switches to open, and thereby place the bank of resistance in circuit with the motor.

30. These objects I attain as hereinafter set forth, reference being had to the accompanying drawing, in which the figure is a diagrammatic representation of one arrangement of apparatus for carrying out my invention.

In the figure, A is the armature of a compound-wound motor having a series field-winding F² and a shunt field-winding f².

R is a bank of starting resistance, and R' is 45 a bank of braking resistance, connected, as hereinafter described, so as to be placed across the armature-terminals of the motor when it is desired to bring it to a standstill.

B is the main switch, to which current-supply wires are connected, and C is an over-

load-circuit breaker of any desired construction, having one terminal connected to the positive pole of the switch B and its second terminal connected to one end of the bank of resistance R.

55. R², R³, R⁴, and R⁵ are automatically-operated switches, each having one terminal connected to a different point of the bank of resistance R and their second terminals all connected together and in series with two coils 60 d and d', also in series, whose free terminal is in turn connected to the wire connecting the resistance R and the circuit-breaker C. Coils r², r³, r⁴, and r⁵, respectively, control the operation of the switches R² to R⁵, inclusive, being connected so as to operate automatically in the manner described and claimed in my application for patent, Serial No. 211,210. It may be stated, however, that one terminal of each coil is connected to that terminal of its switch which is in direct communication with the resistance R, while all of the second terminals of said coils are connected to each other and to the negative supply-main through segments h² and operating-lever h² of a reversing-75 switch H. In the case of switches R³, R⁴, and R⁵ there is interposed in the circuits of their respective coils auxiliary switches r⁶, r⁷, and r⁸, the switch r⁶ being controlled by a contact carried on the blade of the switch R², the switch r⁷ being similarly controlled by a contact on the blade of switch R³, and so on. In the case of the coil r², belonging to the switch R², there is connected in series with it two switches d² and d³, whose opening and closing are controlled by plungers operating under the action of the coils d and d'—that is to say, when the plungers of the said coils are actuated contact-bar g² is moved out of engagement with the contacts of its particular 85 switch, so as to open-circuit the coil r².

In addition to the above switches there are two pairs of switches E and E' and F and F', which together constitute a reversing-switch for the motor A, there being in addition a 95 switch S, so connected that when closed it short-circuits the motor-armature through the bank of resistance R'. The coil of this latter switch is permanently connected directly across the terminals of said armature, so that

it is excited whenever the armature is in rotation. Coils e , e' , f , and f' each have one terminal permanently connected to the circuit-breaker C , which will be seen to be connected to the positive side of the supply-line, while the second terminals of coils e and e' are connected together and to segment h^2 of switch H . Similarly, the second ends of coils f and f' are connected together and to segment h^4 of switch H .

Under operating conditions, with both the main switch B and the circuit-breaker C closed and the lever h^2 of switch H in its central position, there will be no flow of current other than through the shunt-field f^2 of the motor. If now the operating-lever of switch H be moved into the position shown, current will flow from the positive supply-main to coils f and f' , energizing them and causing their respective switches F and F' to close. This will permit current to flow to the armature and series field of the motor, so as to start the latter, such flow taking place from the positive supply-main through switch B , circuit-breaker C , all of resistance R , switch F' , armature A , switch F , series field f^2 , and to the negative supply-main through switch B . As the counter electromotive force rises the current flowing through the resistance R will decrease, thus increasing the voltage applied to the coil r^2 , inasmuch as said coil is excited by the line voltage minus the drop through the first section of the resistance R until finally said coil r^2 is sufficiently energized to close switch R^2 , and with it switch r^6 . This cuts out a portion of the starting resistance R and still further speeds up the motor, after which switches R^3 , R^4 , and R^5 are successively closed until finally all of said resistance R is short-circuited and the motor is operated at full speed. If the motor be so connected as to actuate the jaws of a clam-shell bucket—such as is employed in the handling of ore, coal, &c.—it is frequently found that said jaws often dig into the ore, so as to entrain a greater quantity thereof than the bucket will hold. This under operating conditions would throw a considerable overload on the motor and might cause such an increased flow of current as would seriously injure said motor or strain the machinery. With the arrangement of parts shown, however, by the time the current has increased to a predetermined point either one or both of the plungers have been drawn into their respective coils d and d' , so as to move either one or both of the bars g^4 , with the result that the operating-coil of switch r^2 is open-circuited. Said latter switch therefore immediately opens and by opening the first auxiliary switch r^8 causes switches R^1 , R^2 , and R^3 to also open, thus throwing all of the resistance R into circuit with the motor. This resistance immediately cuts down the current to a safe amount; but in view of the heavy load upon the motor the armature

will be stalled, so as to be incapable of revolving. If now the bucket be raised so as to permit part of the ore or coal to fall from the jaws, it will be possible for the motor to again safely operate, and inasmuch as the bars g^4 of switches d^2 and d^4 have immediately closed said switches as soon as the current flowing to the motor has been reduced by the cutting in of resistance R the armature will speed up, and if the load be within safe limits the switches R^2 , R^3 , R^4 , and R^5 will again successively short-circuit the various portions of resistance R , so as to bring the motor a second time up to full speed. If the operating-handle h^2 of the switch H be moved so as to engage the segments h^1 , h , and h^4 , there will be an interval during which it contacts only with segments h^1 . During this time the coil s of switch S , which, as before noted, is constantly energized from the armature of the motor, causes said switch to close, thus short-circuiting said armature through resistance R and speedily bringing it to a standstill. Even though switches E and E' have their coils e and e' excited from segment h^1 , these switches cannot close, since, as described in a previous application for patent, they are provided with locking-bars e^2 and e^4 , of which the first prevents switch E being closed when switch F is closed, and the second prevents either switch E' or F' being closed while switch S is closed, and vice versa. As soon, therefore, as the armature A has come to rest coil s is no longer energized and switch S automatically opens, thereby permitting coil e' of switch E' to close said latter switch, which, since switch E is already closed, permits the above-described cycle of operations to again take place, though with the direction of rotation of the armature reversed.

From the above it will be seen that by my invention I automatically cut down the current flowing to the motor when the load thereon rises to such a point that said current might reach an injurious volume and as soon as the overload is removed cause automatic acceleration of the motor to its normal speed.

I claim as my invention—

1. A system including an electrically-operated device, current-limiting means therefor, an electromagnetic switch for controlling the introduction of said current-limiting means into circuit with said device, a second electromagnetic switch connected to short-circuit the current-limiting means, a throttle-switch in circuit with the actuating-coil of the first switch, and means in circuit with the electrically-operated device and the second switch for actuating said throttle-switch, substantially as described.

2. A system including a motor, current-limiting means therefor including automatic switches having a winding or windings connected so that their operation depends on the current-flow through the said limiting means,

- with mechanism for cutting said means into circuit with the motor when the current-flow reaches a predetermined maximum and subsequently cutting said means out of circuit when the current has fallen below said maximum, substantially as described.
3. A system including a motor, a body of resistance, an electromagnetic switch or switches for controlling the introduction of said resistance into circuit, a switch in circuit with the coil or coils of the said electromagnetic switch or switches and means actuated by abnormal flow of current to the motor for operating said switch to cause the electromagnetic switch or switches to cut the resistance into circuit with said motor, substantially as described.
4. A system including a motor, a body of resistance, a plurality of automatic switches having their windings connected so that their operation depends on the current-flow through said resistance, and means actuated by an abnormal flow of current to the motor for causing said switches to place the resistance in circuit with said motor, substantially as described.
5. A current-controlling system including a motor, a body of resistance, a series of switches for governing the introduction of said resistance into circuit, a throttle-switch for governing the operation of the switches of said series, with mechanism operated by the current flowing to the motor for causing operation of said throttle-switch, said throttle-switch and the series of switches being connected to automatically control the current-flow to the motor after the resistance has been cut out, substantially as described.
6. A current-controlling system including a motor, means governing the current-flow thereto, a throttle-switch connected to control the operation of said means after the motor has been accelerated, and means in circuit with the motor for controlling the operation of said throttle-switch, substantially as described.
7. A current-controlling system including a motor, means for governing the current-flow thereto, a throttle-switch connected to control said means after the motor has been accelerated, a winding in circuit with said motor, and mechanism actuated by said winding for causing operation of the throttle-switch, substantially as described.
8. A current-controlling system including a motor, means for governing the current-flow thereto including a series of electrically-actuated switches, a throttle-switch connected to control said switches, a winding in circuit with the motor, and mechanism actuated by said winding for causing operation of the throttle-switch, the connections of said apparatus being such that the opening of the throttle-switch causes the opening of said series of switches, substantially as described.
9. The combination of an electric motor, a body of starting resistance, means for automatically utilizing said body of resistance in case of overload for limiting the current flowing to the motor, and means for automatically cutting out said resistance to accelerate said motor after such overload has been removed, substantially as described.
10. The combination of a motor, a bank of resistance, automatic switches for controlling the amount of said resistance in circuit with said motor, with means for causing the de-energization of the coils of said switches, said means including a switch and operating means therefor connected in circuit with the motor, substantially as described.
11. The combination of a motor, a bank of resistance, automatic switches for controlling the amount of said resistance in circuit with said motor, an auxiliary switch in circuit with the winding of one of said switches, means whereby the operation of the auxiliary switch is made to cause opening of the other switches, and means, actuated by the current passing through the motor, for operating said auxiliary switch, substantially as described.
12. The combination of a motor, a bank of resistance, automatic switches for controlling the amount of said resistance in circuit, auxiliary switches in circuit with the coils of certain of the automatic switches and placed to be operated by others of said switches, one of said auxiliary switches being connected to control all the others, with means including a device connected to be actuated by abnormal current-flow through the motor, for causing the operation of the controlling one of the automatic switches, substantially as described.
13. The combination of a series of automatic switches, a bank of resistance and a motor connected thereto, auxiliary switches in circuit with the windings of certain of the switches, one of said auxiliary switches being connected to control the operation of the remainder, a winding in series with the motor-armature and means actuated by said winding for causing operation of controlling auxiliary switch, substantially as described.
14. The combination of a series of automatic switches, a bank of resistance and a motor connected thereto, auxiliary switches in circuit with the windings of certain of the switches, one of said auxiliary switches being so connected that its opening causes the opening of said automatic switches, a winding in series with the motor-armature, means for normally maintaining the controlling auxiliary switch in a closed condition and an armature actuated by said winding and placed to open said auxiliary switch under predetermined conditions of current-flow, substantially as described.
15. A system including a motor, a bank of resistance, a series of automatic switches for controlling the introduction of said resistance

into circuit with the motor, a throttle-switch connected to control the operation of one of said automatic switches, means controlled by said automatic switch for governing the operation of the remaining switches, means in circuit with the motor for governing the operation of the throttle-switch and a hand-operated switch in circuit with the throttle-switch, the windings of said automatic switches being connected so that their operation depends on the current-flow through said resistance, substantially as described.

16. The combination of a motor, means for controlling the acceleration of the same, said means including a current-limiting device, with means for placing said device in circuit when the motor is overloaded, and subsequently cutting out said device when the load on the motor has been reduced, substantially as described.

17. The combination of a motor, a body of resistance, automatic switches for controlling the introduction of said resistance into circuit, with additional means for placing the resistance in circuit with the motor after said switches have been operated, when the current-flow to the motor reaches a predetermined maximum, and subsequently cutting said resistance out of circuit when said current falls below said maximum, substantially as described.

18. The combination of a motor, a bank of resistance, automatic switches connected to said two devices, with a throttle-switch having operating means responsive to a predetermined current-flow through the motor, and connected to cause opening of said automatic switches when it is opened, substantially as described.

19. The combination of a motor, a bank of resistance, automatic switches connected to said two devices, the connections of the windings of the switches being made so that the operation of said switches depends on the current in the resistance, with a series of auxiliary switches including a throttle-switch for controlling the action of said automatic switches, and means including a winding in circuit with the motor-armature for controlling the throttle-switch, substantially as described.

20. A system including a motor, a body of resistance, a switch or switches connected to said two devices, with means actuated by abnormal normal current-flow to the motor for causing said switches to cut the resistance into circuit with the motor, automatic switches for reversing the direction of rotation of the motor and a switch for controlling the operation of said automatic switches, substantially as described.

21. A system including a motor, a body of resistance, a switch or switches connected to said two devices, means actuated by abnormal

current-flow to the motor for causing said switches to cut the resistance into circuit with the motor, means for reversing the motor, and a switch for short-circuiting the motor on itself, substantially as described.

22. A system including a motor, a bank of resistance in series therewith, switches connected to short-circuit portions of said resistance when they are closed, auxiliary switches in circuit with the windings of certain of the resistance-switches and controlled by switches other than the ones which they control, a throttle-switch in circuit with the winding of one of the resistance-switches and means including a winding in circuit with the motor for controlling said throttle-switch, the connection of said apparatus being such that the opening of the throttle-switch causes opening of the resistance-switches, substantially as described.

23. A system including a motor, a bank of resistance in series therewith, switches connected to short-circuit portions of said resistance when they are closed, normally open auxiliary switches in circuit with the windings of certain of the resistance-switches and connected to switches other than the ones which they control, so that they are closed only when said switches are closed, a normally closed throttle-switch in circuit with the winding of one of the resistance-switches, a winding in series with the motor, and mechanism actuated by said winding for opening said throttle-switch, substantially as described.

24. A system including a motor, a bank of resistance, switches for controlling the amount of said resistance in circuit with the motor, auxiliary switches each in circuit with the winding of one of the resistance-switches and controlled by another of said switches, a throttle-switch connected to the winding of a resistance-switch, automatic means operated by current flowing to the motor for actuating the throttle-switch and a hand-controller including a switch in circuit with the throttle-switch, the connection of said apparatus being such that the opening of the throttle-switch causes the remainder of the switches to open, substantially as described.

25. The combination of a motor, with means for automatically reducing the motor-current when the motor is over-loaded after it has been brought up to speed, said means being connected to automatically accelerate the motor when its overload has been removed, substantially as described.

In testimony whereof I have signed my name to this specification in the presence of two subscribing witnesses.

ARTHUR C. EASTWOOD.
